UNITED STATES PATENT OFFICE.

MORRIS J. GARDNER, OF YORK, PENNSYLVANIA.

OSCILLATING STEAM-ENGINE.

Specification of Letters Patent No. 9,954, dated August 23, 1853.

To all whom it may concern:

Be it known that I, MORRIS J. GARDNER, of York, in the county of York and State of Pennsylvania, have invented a new and 5 useful Improvement on Oscillating Steam-Engines; and I hereby declare that the following is a full and exact description thereof, reference being had to the accompanying drawings and to the letters of reference 10 marked thereon.

The nature of my invention consists in the manner of introducing the steam through circular tubes into the steam chest, and at the same time constituting these 15 tubes the circle around which the cylinder oscillates, in the manner substantially set forth, and I do hereby declare that the following is a full and exact description thereof, reference being had to the accompanying 20 drawings, and to the letters of reference marked thereon.

To enable others skilled in the art to make and use my invention, I will proceed to describe its construction and operation.

Upon the steam cylinder, made in the ordinary way, I construct and fix permanently, a circular steam chest and packing boxes, making the journal the center of the segment of the circle which the tubes 25 describe, and which the cylinder necessarily 30 makes, as it oscillates over these tubes.

On Plate No. 1 Figure 1 sets forth a front external view of my improvement. *a, a*, are the circular tubes through which the 35 steam passes into the steam chest and cylinder, being made stationary on the frame of the engine. *b, b* are larger circular tubes attached to the steam chest, inclosing the circular steam tubes. These larger tubes, 40 are of sufficient size to admit of the necessary packing, and also to glide over and around the circular steam tubes. *c, c*, is the external plate covering the steam chest, and firmly secured by screws or bolts, passing 45 through the steam chest into the body of the cylinder. In the middle of this external plate are two set screws *d, d*, for the purpose of adjusting a steel plate, back of the valve in the steam chest, to keep the 50 valve tight on the steam ports when the motion is reversed.

Fig. 2, on Plate No. 1, represents the steam cylinder, with a side view of the steam tubes—larger circular tubes and packing 55 boxes.

Plate No. 2, Fig. 1, gives an internal

view of the whole improvement, showing the manner in which by means of the circular steam tubes, the steam is introduced into the steam chest and from thence into the cylinder. Also a view of the dissected half of the larger tubes (constituting at the same time the packing boxes) which pass over the steam tubes as the cylinder oscillates, and also a view of the packing by which 60 it is secured from leakage. *a, a*, are the steam tubes, that on the right hand the induction and that on the left the eduction tube. *C*, is one of the steam ports for the admission of steam into the cylinder—the 65 other corresponding steam port being hid from view by the valve connected with the eduction tube, as seen at *c* marked with dotted lines. *C*, also represents the valve connected with the eduction tube, which as 70 the cylinder oscillates, alternately opens and closes the steam ports, for the admission of steam into the cylinder and at the same time, for the escape of the exhaust steam through 75 the eduction tube.

Fig. 2 is a hollow tubular screw, through which the steam tubes pass, as the cylinder oscillates. This screw is made to screw into the packing boxes attached to the steam chest, at the inner end of the screw, is a 80 85 projection which is hollow as seen at *d*.

Fig. 3 gives a side view of the screw.

Fig. 4 gives a view of the knob or top of the screw. Into the hollow projection of this screw, is inserted a self-adjusting ring, 90 a little smaller than the hollow projection in the screw, so that it may readily adjust itself, both to the packing and the steam tubes. This ring is beveled on the inside so as to render more compact the packing, 95 and press it against the tubes.

Fig. 5 gives an end view of the screw with the ring in it.

Fig. 6 gives a side view of the ring, the dotted lines represent the bevel of the ring. 100

The manner in which these screws are inserted into the packing boxes is seen at *e, e*, and the manner in which the adjusting ring compresses the packing, and presses it against the tubes, is seen at *f, f*. One of 105 these screws is inserted at each end of the circular steam chest and packing boxes.

To reverse the motion, all that is necessary will be to have an ordinary steam chest communicating with the circular steam 110 tubes and with a slide valve, to make the educting the inducting, and the inducting

the educting tube, and thus changing the force of the steam from one to the other.

The principal advantage of this improvement is to have the oscillation operating in 5 packing and not in metal and thus gaining power by avoiding the friction occasioned by metal operating against metal. The improvement may also be successfully employed as a water pump and a blower for 10 furnaces.

What I claim as my improvement is—

The mode of introducing the steam—the circular steam tubes, the circular steam chest

and packing boxes operating in the manner herein described. I do not however confine 15 my claim to the precise position or dimensions, of the various parts described in the foregoing specifications, but to use such positions and dimensions substantially the same, as may be best adapted to produce the 20 desired effect.

M. J. GARDNER.
